UNITED STATES PATENT OFFICE

172,986

LAMP STAND OR SIMILAR ARTICLE

Alfred Pinterally, Chicago, Ill.

Application October 1, 1953, Serial No. 27,036

Term of patent 14 years

(Cl. D48—20)

To all whom it may concern:

Be it known that I, Alfred Pinterally, a citizen of the United States and a resident of Chicago, in the county of Cook and State of Illinois, have invented a new, original, and ornamental Design for a Lamp Stand or Similar Article, of which the following is a specification, reference being had to the accompanying drawing, forming a part thereof.

In the drawing:

I claim:

The ornamental design for a lamp stand or similar article, substantially as shown.
